UNITED STATES PATENT OFFICE.

BENJAMIN J. PLEASANCE AND PETER A. PATTERSON, OF CLEVELAND, OHIO.

HOISTING AND CONVEYING APPARATUS.

SPECIFICATION forming part of Letters Patent No. 391,423, dated October 23, 1888.

Application filed November 7, 1887. Serial No. 254,550. (No model.)

To all whom it may concern:

Be it known that we, BENJAMIN J. PLEASANCE and PETER A. PATTERSON, of Cleveland, in the county of Cuyahoga and State of Ohio, 5 have invented certain new and useful Improvements in Hoisting and Conveying Mechanism; and we do hereby declare the following to be a full, clear, and exact description of the invention, such as will enable others skilled in 10 the art to which it pertains to make and use the same.

Our invention relates to improvements in hoisting and conveying apparatus designed more especially for coal and ore trade; and it 15 consists in certain features of construction and in combination of parts hereinafter described, and pointed out in the claims.

In the accompanying drawings, Figure 1 is a side elevation. Fig. 2 is a plan of the cable 20 system for hoisting and operating the carriers. Fig. 3 is a plan of the boom, the supporting-chords being in section; and Fig. 4 is a side elevation, partly in section, of the same. Fig. 25 5 is a plan of the boom-hinge, and Fig. 6 is a side elevation of the same. Fig. 7 is a cross-section of the truss and track. Fig. 8 is an enlarged sectional view through the carrier B; and Fig. 9 is a transverse section on line xx , Fig. 6.

30 A represents a suitable truss, to which are attached the track-rails A^2 , arranged in pairs, and on which tracks the respective wheel-carriers B and B' travel. These carriers are supposed to be alike, but have different letters 35 applied for convenience. A boom, C, extends from and is hinged to the one end of the truss, so that it may be raised or lowered, as circumstances may require, in loading and unloading vessels. The chords A' of the truss are preferably of plate metal set edgewise, while the track-rails A^2 may be of ordinary railroad-iron set with their bases against the chords, to which the track-rails are secured on either 40 side of the respective chords, so as to break 45 joints with each other and with the sections of the chord.

F is the hoisting-cable, and also operates the carriers. The respective ends of the cable are attached to drums D and D'. These drums 50 are provided with the necessary gearing, friction-clutches, &c., for revolving the drums

simultaneously at the same speed, and for reversing the drum, and for operating either drum independent of the other drum. The gearing, clutches, &c., for thus operating the 55 drum are not shown; but such mechanism is well understood, and any of the several varieties already in use will answer the purpose.

From the driving-drum the cable, after passing over the necessary guiding-pulleys—for 60 instance, as shown in Fig. 1—runs over idle-sheave b , connected with each carrier, and from thence runs under sheave e , connected with bail E' of the respective hoisting-buckets E. From the carriers the cable leads around a 65 lateral wheel, c , located at the outer end of the boom. In fastening the cable to the respective carriers enough length of cable is left between the carriers to reach from the hoisting-points around the lateral wheel to the 70 dumping-point. Almost any device for clamping the cable fast to the carrier will answer the purpose. The device shown, however, consists of blocks F' , with set-screws f' , for pressing the blocks onto the cable and pressing the 75 cable into notches f^2 , made in the wall of the carrier. The buckets are flaring, as shown, and have heavy bottoms, and the bails E' are pivoted to the sides of the buckets above the center of gravity of the bucket, by reason 80 of which the loaded bucket, when left free, will tilt and dump by gravity, while the empty bucket will by gravity assume an upright position.

In operating the device, suppose carrier B, 85 with a loaded bucket attached, is at the dumping-station, and carrier B', with an empty bucket, is at the loading-station, both buckets being in their elevated positions. By slackening off the cable from drum D the loaded 90 bucket would be lowered and dumped, whereupon drum D is stopped. By slackening off the cable from drum D' the empty bucket would be lowered for loading. As soon as the bucket is loaded or a loaded bucket is substituted, as 95 the case may be, by reversing drum D the dump-bucket is drawn up against the carrier B, and by reversing drum D' the loaded bucket is drawn up against the carrier B', after which, by continuing the movement of drum D' and 100 slackening off the cable from drum D, if the drums move at the same speed, the cable

will be kept taut, holding the buckets against their respective carriers, and carrier B' will be drawn to the dumping-station simultaneously with carrier B reaching the loading-station. The lowering of the empty bucket at the loading-station may be done while the loaded bucket is being lowered and dumped at the dumping-station. The tracks converge on the boom, the inner tracks crossing each other, as shown in Fig. 3, so that when the end c' of the boom is reached the carriers from the different tracks are approximately in the same position over the hold of the vessel. The boom may be raised or lowered from a horizontal position to bring the buckets in the desired position crosswise of the vessel. As such variation of the boom would cause angles in the line of the track-rails, we provide short track-sections a, a', and a''. (See Figs. 5 and 6.) These short track-sections are usually of cast metal and extend from one track to the other of the same chord, forming a section or part of each of the tracks. These track-sections are jointed together, being made with interlocking ends secured by pintle a³. Bails A³ connect with two of these pintles of each set of tracks, as shown, the bails being placed astride the chords, each bail having a set-screw, A⁴, abutting the upper edge of the chord, by means of which the bails may be raised or lowered a limited distance, thereby raising or lowering the connected joints of the track-sections a, a', and a''. Section a is jointed to the contiguous stationary track-rail, and section a'' is made wedge-shaped and rests on the correspondingly wedge-shaped end of the adjacent track-rail. By means of the bails and set-screws just described these track-sections may be adjusted to divide the angle of the track caused by raising or lowering the

boom at four points, so that the carrier-wheels will run smoothly past the axis of the boom. Arms H are located beneath the cable to receive and hold the same when any slack is produced.

45

What we claim is—

1. The combination, with double tracks and a pivoted boom having tracks thereon converging at the one end to substantially a common hoisting-station, of carriers for traveling on the respective tracks, a cable adjustably secured to the respective carriers, drums connected with the ends of the cable for operating the latter, and a lateral wheel set at the terminus opposite the drum for supporting the cable, substantially as set forth.

2. The combination, with a truss having double tracks thereon, of a boom hinged to one end of such truss to swing in a vertical plane, said tracks converging on the boom to substantially a common hoisting-station, and a cable having carriers connected therewith, substantially as set forth.

3. The combination, with a truss and boom pivoted to the truss, of jointed track-sections adjacent to the pivotal point of the boom and bails and set-screws, substantially as indicated, for adjusting such track-sections, whereby a continuous curve is formed in the track at the pivotal point of the boom when the latter is changed from a horizontal position, substantially as set forth.

In testimony whereof we sign this specification, in the presence of two witnesses, this 2d day of June, 1887.

BENJAMIN J. PLEASANCE.

PETER A. PATTERSON.
